HYDRAULIC FLOW CONTROL DEVICE

Raymond J. Miller, Detroit, Mich., assignor to
 Dearborn Motors Corporation, Birmingham,
 Mich., a corporation of Delaware

Application June 23, 1951, Serial No. 233,184

3 Claims. (Cl. 138—45)

1

This invention relates to a fluid flow control device for pressured hydraulic fluid systems.

The application of hydraulically operated motors to perform useful work are many and varied. In certain applications where the hydraulically operated piston of a cylinder is utilized to raise a load, it is customary to permit such load to lower by gravity by diverting the flow of pressured fluid from the cylinder to the oil reservoir and bleeding the oil in the cylinder back to the reservoir.

A specific example of the above mentioned use of hydraulic power is the case of a loader mounted on a tractor wherein hydraulically operated pistons are utilized for elevating the loader boom to a raised transporting or unloading position. In this specific illustration, the loader boom is generally arranged to lower to the ground by gravity. To permit the loader boom to lower to the ground, the fluid in the cylinders is permitted to flow freely back to the sump or reservoir as the force of gravity drives the piston in the cylinder downwardly. Unfortunately, however, the rate of fall of the loader boom is relatively unrestrained so that the boom lowers at a rapid rate. This results in the loader boom striking the ground with considerable velocity which obviously is harmful to the various components of the boom as well as the loader and tractor. Admittedly, a measure of control can be exercised in lowering the loader boom by proper manipulation of the control valve. This procedure, however, does not appreciably slow the rate of fall of the loader bucket as all that is accomplished is a lowering of the boom in a series of short drops; each drop producing a reaction on the loader frame and hence on the tractor as the downward movement of the loader is abruptly arrested. Another, and perhaps more serious drawback to so lowering the loader is the danger of rupturing the fluid supply conduits leading to the cylinder. The sudden stopping of the loader boom at any point sets up extremely large internal pressures in the cylinder and the conduits which occasionally results in rupture of such conduits.

Accordingly, it is an object of this invention to provide an improved hydraulic fluid flow control device for automatically effecting a substantial reduction in the flow of pressured fluid through a conduit in one direction; for example, for controlling the rate of fluid discharge from a cylinder.

Another object of this invention is to provide an improved hydraulic flow control device which may be conveniently adapted for use with any

2

pressured fluid system wherein the rate of flow of pressured fluid in a certain direction may be automatically retarded, without interference with fluid flow in the opposite direction.

5 A further object of this invention is to provide a hydraulic flow control device which is operable in response to a pressure differential on opposite sides of such device for effecting a substantial reduction of flow of the pressured fluid in one direction through such device.

10 The specific nature of this invention, as well as other objects and advantages thereof, will become apparent to those skilled in the art from the following detailed description, taken in conjunction with the one sheet of drawings on which, by way of preferred example only, is illustrated several embodiments of this invention:

On the drawings:

Figure 1 is a schematic view of a hydraulic system having a fluid operated motor in which the improved flow control device constructed in accordance with this invention is incorporated.

Figure 2 is an enlarged detail sectional view of a preferred form of the fluid control device.

25 Figure 3 is a view similar to Figure 2 but showing the constriction of the fluid passage of such device when subjected to hydraulic fluid flow in a certain direction.

Figure 4 is a view similar to Figure 2 but showing a modified securing device for preventing axial movement of the flow control device.

30 Figure 5 is a further modification of the device shown in Figure 2.

Figure 6 is a modification of the structure shown in Figure 5 particularly as regards the flow control securing device.

As shown on the drawings:

35 The fluid flow control device of this invention, to be shortly described in detail, is useful in numerous applications wherein it is desired to restrict the fluid passageway of a pressured fluid system in order to reduce the flow of fluid through such passageway in one direction in response to a sudden change in pressure differential in the system. Its application is best suited to a pressured fluid system which incorporates a hydraulic cylinder with cooperating piston wherein the power stroke of the piston is utilized to move a load, and where gravity acts upon such load to

40 return the piston to its original position. In this case, it is desirable that the fluid bled from the cylinder pass through a restricted orifice to substantially reduce the rate of flow of the fluid, and hence the rate of fall of the load.

45 Accordingly, there is shown schematically in

Figure 1 a pressured fluid system which includes a hydraulic cylinder C having a cooperating piston R. A pump P delivers pressured hydraulic fluid from a sump or reservoir S through a conduit B, in which a hydraulic flow control device FC is inserted, to one end of cylinder C. A valve V is connected in series with pump P whereby pressured fluid from pump P may be selectively diverted to cylinder C or returned to sump S through a conduit D. When valve V is positioned to divert the pressured fluid from pump P back to the sump, the hydraulic fluid contained in cylinder C will then be drained back to sump S also through conduit D.

In Figure 2 there is shown a preferred form of the hydraulic flow control device FC which comprises a hollow cylinder 10 of resilient, rubber-like material. The resilient cylinder 10 snugly engages the inner wall of conduit B and such cylinder is provided with an axial bore 10a. Cylinder 10 is positioned in conduit B between valve V and cylinder C and is preferably located relatively close to cylinder C. An annular groove 10b is provided in the right hand end face of resilient member 10, as best shown in Figure 2, and such recess is preferably concentric with axial bore 10a. A disc 11 having an axial aperture 11a is placed against the right hand face of resilient member 10 so that aperture 11a is in alignment with axial bore 10a of the resilient member 10. An annular groove 12 is provided in the interior wall of conduit B next to disc 11 and a snap ring 13 is forced into annular groove 12; thus, snap ring 13 provides a stop against which disc 11 abuts to restrict axial movement of resilient member 10 in a right hand direction, as shown in Figure 2. Disc 11 closes off the outwardly opening recess 10b provided in resilient member 10. However, a plurality of transverse holes 11b in disc 11 communicate with recess 10b for a purpose to be later described.

When it is desired to utilize piston R for raising a weight W, valve V is adjusted to permit pressured fluid from pump P to enter cylinder C. The pressured fluid flows through conduit B and through the flow control device FC. The pressured fluid passes through aperture 11a of disc 11, thence through the axial bore 10a of resilient member 10. Simultaneously, however, pressured fluid enters annular recess 10b in resilient member 10 through transverse holes 11b in disc 11. Therefore, no appreciable deformation of resilient member 10 results when pressured fluid from pump P flows through the hydraulic fluid flow control member 10 as the pressure on both sides of resilient member 10 are equalized and hence axial bore 10a is not constricted.

When pressured fluid from pump P is diverted back to the sump by manipulation of valve V, hydraulic fluid will then be bled out of cylinder C to return to sump S through conduit D. When such happens, however, the pressure on the pump side of the resilient member 10 immediately drops to a low value while the weight W acting against piston R through the force of gravity maintains a relatively high pressure on the other side of resilient member 10. The fluid pressure in annular recess 10b is also reduced, due to the apertures 11b. Hence, the pressure differential between the opposite sides of resilient member 10 acts against the left hand end area of resilient member 10 to deform such member to the shape shown in Figure 3 and thus constricting bore 10a as shown at 10c. Constriction of bore 10a substantially reduces the rate of flow of pressured

hydraulic fluid through such bore, thus increasing the length of time required to drain the fluid from cylinder C and hence effecting a substantial reduction in the lowering rate of weight W. Furthermore, the extent of such constriction is a direct function of the pressure differential, hence shock loads are effectively minimized.

It will be noted that the resilient member 10 is compressible in response to a pressure differential between its opposite ends and only when the flow of hydraulic fluid is from the cylinder C to the sump S. Such response may be referred to as a unidirectional pressure differential response which simply means that resilient member 10 is compressed only by a pressure differential producing one direction of flow of the hydraulic fluid through such resilient member, but is unaffected by a pressure differential producing direction of flow in the opposite direction. Of course, since amount of constriction produced by resilient member 10 is a function of the pressure difference, the rate of lowering movement of the piston R is substantially independent of the mass of load weight W.

Figure 4 illustrates a modified arrangement for restricting axial movement of resilient member 10. Such device comprises a collar 14 having inwardly facing edge flanges 14a and 14b respectively provided on the opposite edges thereof. The collar 14 surrounds resilient member 10 and the disc 11 is placed between resilient member 10 and the flange 14a, as shown in Figure 4. Flange 14b can engage the left hand end face of resilient member 10, or if preferred, a washer 15 may be placed between flange 14b and resilient member as shown. When resilient member 10 and disc 11 are joined together by collar 14, the entire assembly is then press-fitted within the bore of conduit B. Thus, the tight fit produced between collar 14 and conduit B effectively resists axial movement of the assembly under the influence of an unbalanced hydraulic pressure within the conduit B.

Figure 5 illustrates a further modified form of the hydraulic flow control device wherein a resilient compressible member 16 of annular, U-shaped, cross section is provided for insertion in conduit B. In this modification, resilient member 16 has an annular groove 16b formed in its outer periphery. An axial bore 16c is provided in resilient member 16 and an angularly directed fluid passageway 16d communicates groove 16b with the end of axial bore 16c, remote from cylinder C. This fluid passageway 16d exits at a point adjacent the right hand end face of resilient member 16. A pair of washers 17 and 18 are respectively provided on opposite sides of resilient member 16, the resilient member 16 being bonded to one of the washers 17 or 18. Resilient member 16 and washers 17 and 18 are held in assembled relationship within a desired location in conduit B by a pair of collars 19. Collars 19 are respectively provided with an edge flange 19a. Collars 19 are assembled within conduit B, one inside of the other, with the edge flanges disposed in opposed relationship so that such flanges will respectively engage the end faces of washers 17 and 18. Collars 19 are press-fitted into conduit B so that axial movement of the resilient member 16 is thereby effectively eliminated.

A modification of the construction shown in Figure 5 is illustrated in Figure 6. In such figure resilient member 16 is fitted within a collar 20 which has an edged flange 20a. Collar 20 is

press-fitted into the bore of conduit B and resilient member 16', similar to resilient member 16, has a peripheral flange 16a which is flared outwardly somewhat, as shown in Figure 6, to contact the inner wall of collar 20. A washer 21 abuts flanges 20a of collar 20 and resilient member 16 abuts washer 21. It will be appreciated that the washer 21 can readily be eliminated by increasing the radial width of flange 20a against which the adjacent face of resilient member 16 can abut.

The modifications illustrated in Figures 4, 5 and 6 function in substantially the same manner as that described for the construction illustrated in Figure 2, hence, further description as to the operation of such modifications is not believed necessary.

From the above description, it is clearly apparent that there is here provided an improved fluid flow control device which is not only simple in design and economical to manufacture, but is positive in operation to unidirectionally reduce the rate of fluid flow in a conduit in response to creation of a unidirectional pressure differential in such conduit. This control device is not limited to use in any one particular hydraulic system, but has a large number of applications wherein an automatic unidirectional restriction of the flow of pressured fluid in the system is desired in order that the rate of movement of the hydraulic piston in the system may be appreciably slowed.

It will, of course, be understood that many details of construction may be varied through a wide range without departing from the principles of this invention and it is, therefore, not the purpose to limit the patent granted hereon otherwise than necessitated by the scope of the appended claims.

I claim:

1. For use in a reversible flow fluid conduit, a unidirectional flow control device of resilient material positionable in said conduit, said flow control device having a passage therethrough permitting fluid flow through said conduit, said flow control device defining a recess separate from said passage, said recess being in fluid communication with said conduit only at one end of said flow control device, whereby a pressure differential across said flow control device producing flow through said flow control device toward said one end produces a distortion of the resilient material of said flow control device surrounding said recess to constrict said passage.

2. The combination defined in claim 1 wherein in said passage comprises an axial bore through said flow control device and said recess is of an annular configuration surrounding said passage.

3. The combination defined in claim 1 plus a rigid plate abutting said one end of said flow control device, said plate having a first aperture aligned with said passage and a second aperture communicating with said recess.
